AMPLIFIER

Charles S. Root, Stratford, Conn., assignor to
General Electric Company, a corporation of
New York

Application June 20, 1939, Serial No. 280,119

14 Claims. (Cl. 179—171)

My invention relates to amplifiers and more particularly to audio frequency amplifiers such as are commonly employed in radio receivers.

It has for one of its objects to provide certain improvements in such amplifiers whereby their cost is reduced and the operation is improved.

More specifically, it has for one of its objects to avoid certain difficulties in such amplifiers resulting from use in connection therewith of loud speakers of the permanent magnet type. Loud speakers for radio receivers have commonly been provided with electromagnetic field coils which are energized from the rectifier which supplies energizing currents to the receiver. These coils, of course, have high inductance and are utilized as smoothing reactors in the rectifier output system thereby to reduce the production of hum at the output of the receiver. Since permanent magnet speakers now coming largely into use have no such coil, the problem is presented of maintaining the production of hum at its former low level and at the same time retaining the reduction in cost of the receiver obtained by substitution of the permanent magnet speaker for the speaker having the electromagnetic field coil.

One of the objects of my invention is to provide means whereby this result is accomplished and whereby it may be accomplished even in receivers having large output volume and in which the production of hum must be kept at a very low level.

Commonly degenerative circuits have been used for reduction of hum. One of the objects of my invention is to effect certain improvements in such circuits whereby the degeneration voltage utilized may be increased and at the same time prevent undesired regeneration at both high and low audio frequencies in the voice range.

The novel features which I believe to be characteristic of my invention are set forth with particularity in the appended claims. My invention itself, however, both as to its organization and method of operation, together with further objects and advantages thereof may best be understood by reference to the following description taken in connection with the accompanying drawing in which the single figure represents an embodiment of my invention.

Referring to the drawing, I have shown therein a two-stage amplifier comprising electron discharge devices 1 and 2. The anode of the electron discharge device 1 is coupled to the grid of the electron discharge device 2 by means of a coupling condenser 3. The anode of discharge device 2 is connected through the primary wind-

ing of an output transformer 4 to the positive side +B of the source of operating current (not shown). This point +B is also connected through a resistance 6 to the screen grid 7 of the electron discharge device 2 and through resistance 8 to the anode of electron discharge device 1. The output of transformer 4 may be connected to the voice coil of a loud speaker or other suitable signal responsive device.

In the form of the invention shown the discharge device 1 is one having a cathode 9 which cooperates with the signal, or control, grid 10 and anode 11 of the amplifier, and also with an anode 12 of a diode rectifier. The circuit of this diode rectifier extends from the anode 12 through the secondary winding of input transformer 13, which may comprise the output transformer of the intermediate frequency portion of the superheterodyne receiver, load resistance 14, resistance 15, and thence to the cathode 9 of the diode. Signal currents appearing on resistance 14 are supplied to the grid 10 of the amplifier in discharge device 1 through coupling condenser 16 and the potentiometer 17, the circuit of this potentiometer being completed through resistances 18 and 15 to the bottom of the diode load resistor 14. The usual diode load bypass condenser 14' is connected between the upper terminal of resistance 14 and the cathode 9 of the diode. This cathode is also connected to the point 28 between resistances 18 and 15. The variable tap 30 on the potentiometer 17 is coupled through condenser 19 to the grid 10 of the discharge device. This grid 10 is also connected to the cathode 35 through a resistance 20 which has a value dependent upon the discharge device 1 employed, such as to provide a suitable bias upon the grid of amplifier 1 produced by its own contact potential.

40 High frequency potentials appearing upon the anodes of discharge devices 1 and 2 are bypassed to the cathodes thereof, as is usual in such amplifiers, by condensers 21 and 22 respectively.

45 The discharge device 2 is preferably one having a screen grid 7 and a suppressor grid 32 and having extremely high impedance between its anode and cathode. A suitable bias voltage for the control grid of this discharge device is provided by means of resistance 23, which is bypassed for signal frequencies by condenser 24. The grid of device 2 is connected to the negative terminal of this resistance 23 through the usual grid resistor 31.

50 Condensers 25 and 26 are the usual smoothing condensers associated with the power supply sys-

tem which is connected between the conductors +B and -B.

In the operation of my invention the intermediate frequency currents of the receiver, which commonly have a frequency of 455 kilocycles, are rectified in the diode 9, 12, the rectified potentials appearing upon resistance 14. The audio frequency components of these potentials are supplied across the potentiometer 17 from which they are coupled by condenser 19 to the grid of amplifier 1. These components are amplified in amplifier 1 and are then supplied through coupling condenser 3 to the grid of amplifier 2 from which they are supplied through the output transformer 4 to the loud speaker, or other suitable audio frequency apparatus.

The anode of the amplifier 2, it will be observed, is connected to the power supply of the receiver at the input side of its output filter, which filter comprises resistance 6 and condensers 25 and 26. Accordingly, considerable amounts of hum currents produced by rectification of the energizing currents, which commonly are of sixty-cycle frequency, are supplied to the anode circuit of the amplifier 2 and these hum currents are likely to be reproduced by the loud speaker. Of course, the application of such hum currents to the anode of the output tube could be reduced by additional filtering but such filtering is expensive and, in addition, it includes elements across which voltage drops appear, making it necessary to use higher voltage transformers in the power supply system.

In accordance with my invention, however, the reproduction of these hum currents is obviated by the use of degeneration in an improved way. This is effected by means of the resistances 15 and 18 in the anode circuit of discharge device 2, across which the diode load 14 and the volume control potentiometer 17 are connected in series. These elements 14, 17, 18 and 15 comprise a bridge and may be so proportioned that the audio frequency voltage with respect to ground, derived from passage of anode current of device 2 through resistances 15 and 18, is substantially the same at the point 27 on the branch 14, 17 of the bridge as at the point 28 on the branch 15, 18 of the bridge. This may be so even at low frequencies—since the coupling condenser 16 may be of very high capacity and low impedance.

It will be observed, therefore, that when the variable contact 30 of the potentiometer is at its upper position, substantially no voltage from resistances 18 and 15 is supplied to the input of the discharge device 1. That is, the voltage of resistances 18 and 15 are both supplied to this point, the voltage of resistance 18 being supplied in degenerative phase and the voltage of resistance 15 being supplied in regenerative phase with respect to the input of discharge device 1, so that the two substantially neutralize each other and no degeneration is produced. Also, at this point the maximum voltage of the source comprising resistance 14 is supplied to the grid of the amplifier. This is the position which the potentiometer would occupy during reception of weak signals as from distant stations.

When the potentiometer contact 30 is moved to its lower position the entire voltage of resistance 18 is supplied to the input of the amplifier. This appears from the fact that the cathode is connected to the point 28 between resistances 15 and 18 and the grid is connected to the upper terminal of resistance 18. Accordingly this voltage is effective upon the grid of the amplifier and

operates in the way common to degenerative systems in reducing hum.

It sometimes happens, in connection with degeneration systems that a phase shift is produced at high frequencies by reason of shunt condensers 21 and 22, and at low frequencies by reason of the coupling condenser 3 and the inductance of the output transformer 4, so that the feed back voltage which is commonly taken from across the output device, and supplied back to the grid becomes so shifted that it becomes regenerative. Such regeneration at high frequencies tends to cause increased amplification at such frequencies, which tends, in turn, to accentuate the reception of noise currents, etc. Such regeneration at low frequencies tends to increase the amplification at low frequencies and, hence, accentuates the undesired hum currents in the output of the system. In short wave radio receivers, this increased low frequency amplification increases the tendency of the receiver to produce howling and fluttering sounds at the reproducer. In fact, such regeneration at both high and low frequencies may be so great as actually to produce continuous oscillations.

To reduce such undesired regeneration the amount of degeneration employed may be reduced. This is undesirable, however, since this increases the production of hum and, in general, reduces the advantages secured through degeneration, such as reduction of distortion, improvement of the frequency characteristic, etc.

In accordance with my invention, increased degeneration may be employed and at the same time this undesired regeneration may be completely avoided.

This result is effected by the arrangement described in that the resistances 15 and 18 from which the feed back voltages are derived are connected in series with the output transformer 4 and in that the discharge device 2 is of very high impedance. This discharge device is one in which the internal anode impedance is so high that it is commonly referred to as a constant current device. That is, the phase of the anode current is not affected at the different frequencies by reason of the reactance of the output transformer or other reactances which may be included in the anode circuit. Since this current is passed through the resistances 15 and 18 from which the feedback voltages are derived, it will be seen that the phase of these voltages are not affected at the different frequencies by the reactance of the output transformer. Thus, no regeneration can be produced by reason of the impedances of the anode circuit of discharge device 2.

The only remaining impedances which might produce phase shift and therefore, regeneration, are condenser 21 and condenser 3 which are included in circuit between the discharge devices. The capacitance of condenser 3 may readily be made sufficiently large and that of condenser 21 sufficiently small, however, with respect to resistor 31 that any phase shift produced by these elements is appreciable only at very low frequencies or at frequencies above the audio range respectively, and even at those frequencies the shift cannot exceed ninety degrees and accordingly the system cannot become regenerative. Accordingly, the only effect of these impedances is to reduce the extent of degeneration, and this reduction, by proper choice of these impedances, may be made small in the usable frequency range.

Condenser 22 may be connected between the anode of discharge device 2 and the point 28 of

the resistances 15 and 18 so that at the high frequencies more audio voltage appears across resistance 18 than appears across resistance 15. In this way, more degenerative voltage is supplied back to the input circuit at high frequency than regenerative voltage, with the result that when the potentiometer 30 is near the upper end of the potentiometer resistance 17, the system is balanced at medium frequencies but is still degenerative at high frequencies so that noise on weak signals is reduced.

Of course, when the potentiometer contact 30 is at the top of the volume control, unless something further were done, the low frequency degeneration voltage would be completely removed. It, therefore, would not be effective to reduce hum, or the tendency above mentioned to produce howl, or flutter, of the receiver. Accordingly, it is desirable that there be some degeneration at low frequencies when the potentiometer is adjusted at this upper position. This may be effected by reducing the capacity of condenser 16 so that the bridge 17, 14, 18, 15 is somewhat unbalanced at low frequencies.

Of course, it is undesirable to make the capacitance 16 too small because to do so would reduce the desired transmission of low and medium frequency potentials from resistance 14 to potentiometer 17. However, resistance 17 may generally be of about 2 megohms resistance and about ten times greater than the resistance of resistor 14. With these elements so proportioned, the capacitance of condenser 16 may be made sufficiently small to produce sufficient unbalance of the bridge at low frequencies to produce the desired degeneration and, at the same time, not materially reduce the desired transmission of low and medium frequency potentials from resistance 14 to potentiometer 17. That is, the reactance of condenser 16, when adjusted for desired degeneration with contact 30 at the top of the potentiometer 17 is relatively small as compared to resistance 17 so that it does not substantially reduce the current produced in resistance 17 by the potential of resistance 14. It is, however, sufficiently large as compared to the resistance 14 to be effective in unbalancing the bridge with respect to potentials produced by the anode current of device 2 flowing in resistances 15 and 18.

One way to adjust condenser 16 is by first inserting a large condenser of, let us say, 1 microfarad in this position and then establish a true balance of the bridge at 400 cycles frequency. After this, contact 30 may be adjusted for good volume of reception from a semi-local station, and the capacity of condenser 16 reduced until the low frequency response of the amplifier is reduced just noticeably. It will then be found that with contact 30 at the top of the volume control there will be sufficient degeneration effectively to reduce hum.

In the drawing, the potentiometer 17 is shown as having its lower portion shunted by the series combination of resistance 33 and capacitance 34 thereby partially to shunt out the medium and high frequencies for so-called base compensation. These elements, of course, influence the value of condenser 16 necessary for desired degeneration with contact 30 at the top of the volume control resistance 17 and if such elements be employed, the value of condenser 16 must be determined with them included in the circuit.

Of course, the balance of the bridge may, as is sometimes desirable, be so adjusted that when

contact 30 is at the top of the volume control a regenerative voltage is supplied to the grid, thereby to increase amplification and sensitivity of the receiver. This may be effected by proper choice of resistances 14, 17, 15 and 18 so that the point of balance falls on potentiometer 17 slightly below the upper terminal of resistance 17, rather than at its upper terminal for medium and high frequencies. Condenser 16 may be sufficiently small so that this regeneration does not exist for low frequencies and, in fact, so that for such frequencies, the system may even be degenerative when contact 30 is at, or near its extreme upper position. In this way advantage 15 of regeneration may be had to increase the sensitivity of the receiver to middle frequencies such as 400 cycles and high frequencies, and, at the same time, hum and the tendency to produce howl and flutter are reduced by degeneration at 20 low frequencies, all with contact 30 at the same position, high on the volume control potentiometer.

It will be noticed that capacitance 14', which is the conventional intermediate frequency bypass condenser for the diode load resistance 14, has its lower terminal connected between resistance 18 and 15 rather than directly to the lower terminal of resistance 14. This is to avoid unbalance of the bridge at high frequencies which 25 would result if this condenser were included in an arm thereof rather than across the diagonal 27, 28 thereof as shown.

Resistance 15 is included in circuit between the cathode and anode of diode 9, 12 but it is 30 sufficiently small in value so that the unidirectional voltage across it does not objectionably affect the operation of the diode. Ordinarily it may be of the order of 10 ohms.

While I have shown a particular embodiment 40 of my invention it will be understood that I do not wish to be limited thereto, since different modifications, both in the circuit arrangements and in the instrumentality employed may be made. I, therefore, contemplate by the appended claims to cover any such modifications 45 as fall within the true spirit and scope of the invention.

What I claim as new and desire to secure by Letters Patent of the United States is:

50. 1. The combination, in an amplifier, of means to supply signals to the input circuit of said amplifier having frequencies extending over a range of signal frequencies, an output circuit for said amplifier including a reactive impedance, 55 the phase characteristics of said impedance and said amplifier being such that if the voltages across said impedance were supplied to said input circuit in proper phase to produce degeneration at low frequencies within said range then undesirable regeneration would occur at high frequencies within said range due to variations in said characteristics with frequency, means to maintain the phase of the currents in said output circuit substantially unaffected by said variations, means responsive to said currents to supply potentials from said output circuit to said input circuit in degenerative phase at all frequencies within said range, and means to vary simultaneously the intensity of said signals supplied to said input circuit and the intensity of said potentials supplied thereto from said output circuit.

2. In combination, a source of audio signals, a signal load, an amplifier connected between 75 said source and load, an impedance in series

with said load, said signal source and a second impedance connected in series across said first impedance, the input of said amplifier being connected between an intermediate point on said first impedance and a point on said second impedance, the second impedance being connected to that terminal of said first impedance from which the voltage of said first impedance is supplied to the input of said amplifier in degenerative phase.

3. In combination, a source of audio signals, a signal load, an amplifier having an input circuit and an output circuit, said output circuit including said load and an impedance in series, the internal output impedance of said amplifier being sufficiently great that the phase of current in said output circuit is substantially unaffected at different frequencies by the external impedance of said output circuit, said source and a second impedance being connected in series across said first impedance, and means for impressing upon said input circuit voltages developed between an intermediate point on said first impedance and a point on said second impedance, whereby said source and said first and second impedances form a bridge connected to supply voltage from said output circuit to said input circuit.

4. In combination, an amplifier operable over a range of frequencies and having an output circuit having reactive impedance such that the phase of the voltage across said impedance varies with frequency, means to supply from said output circuit to the input of said amplifier, in degenerative phase, a voltage having a phase substantially unaffected at the different frequencies in said range by said reactive impedance, a source of signal currents to be amplified connected to said input, and means to vary simultaneously the amount of signal voltage supplied to said input and the amount of degenerative voltage supplied from said output circuit to said input.

5. In an electron discharge amplifier having a pair of input terminals and a pair of output terminals, a load device and a resistance connected in series between said output terminals, a source of signal currents to be amplified and a potentiometer connected in series across said resistance, one input terminal of said amplifier being connected to a variable point on said potentiometer and the other input terminal being connected to an intermediate point on said resistance.

6. In an electron discharge amplifier having a pair of input terminals and a pair of output terminals, a load device and a resistance connected in series between said output terminals, a source of signal currents to be amplified and a potentiometer connected in series across said resistance, one input terminal of said amplifier being connected to a variable point on said potentiometer and the other input terminal being connected to an intermediate point on said resistance, said potentiometer and said signal source having such proportions that when said variable point is moved to one extremity of said potentiometer, substantially no voltage from said resistance is supplied to said input terminals.

7. In combination, a source of signal currents, a load, an amplifier connected between said source and load, a resistance in series with said load, having an intermediate point, the portions of said resistance on opposite sides of said intermediate point, said source, and a second re-

sistance comprising the respective arms of a four-arm bridge, the voltage of said source and the voltage of said first resistance appearing on said second resistance, the input to said amplifier being connected to said second resistance, to receive therefrom both of said voltages, whereby the voltage of one portion of said first resistance tends to produce regeneration of said amplifier while the voltage of the other portion of said first resistance tends to produce degeneration, and means to supply a greater proportion of the output current of said amplifier through said other portion of said first resistance at high frequencies than at low frequencies thereby to increase the degeneration of said amplifier at high frequencies.

8. In combination, an amplifier having a load and an impedance in series therewith, a diode detector having a load resistance and a load condenser, one terminal of said load resistance being connected to one terminal of said impedance and the other terminal of said load resistance being connected to an intermediate point on said impedance through said condenser, the opposite terminal of said impedance being connected to said other terminal of said load resistance through a second resistance, and means to supply potential from said second resistance to the input of said amplifier, said load resistance, impedance and second resistance comprising a bridge having said condenser diagonal thereto.

9. In combination, an amplifier operating over a wide band of audio frequencies including a predetermined frequency of the order of 100 to 400 cycles per second, a feed-back network connected from the output of said amplifier to the input thereof, and means to supply feedback voltages through said network which are in regenerative phase at all frequencies within said band higher than said predetermined frequency and in degenerative phase at all frequencies within said band lower than said predetermined frequency, said voltages being of sufficient magnitudes to increase the sensitivity of said amplifier at said higher frequencies and to decrease the tendency of said amplifier to reproduce hum voltages and to flutter at said lower frequencies.

10. In combination, an amplifier operating over a wide band of signal frequencies extending on either side of a predetermined frequency, means comprising a bridge network interconnecting the output and input circuits of said amplifier for feeding back voltages of said frequencies, said network being balanced at said predetermined frequency and so proportioned that the feedback voltages impressed on said input circuit are regenerative at all frequencies within said band higher than said predetermined frequency and degenerative at all frequencies within said band lower than said predetermined frequency.

11. In combination, an amplifier operating over a wide range of signal frequencies, a volume control adjustment device therefor, and means to supply voltage from the output of said amplifier to the input thereof, said means operating to supply low frequency voltages to said input in degenerative phase for all adjustments of said volume control device and to supply high frequency voltage to said input in degenerative phase for one adjustment of said volume control device and in regenerative phase for a different adjustment of said volume control device.

12. In an electron discharge amplifier having

a pair of input terminals and a pair of output terminals, a load device and a resistance connected in series between said output terminals, a source of signal currents to be amplified and a potentiometer connected in series across said resistance, one input terminal of said amplifier being connected to a variable point on said potentiometer and the other input terminal being connected to an intermediate point on said resistance, said source, potentiometer and resistance forming a bridge to supply voltage from the circuit of said load device to the input of said amplifier, and means so to balance said bridge that when said variable point is in one position on said potentiometer high frequency currents are supplied to said input in regenerative phase and low frequency currents are supplied thereto in degenerative phase while, when said variable point is at a different position on said potentiometer both low and high frequency currents are supplied in degenerative phase.

13. The combination, in an audio amplifier including a plurality of electron discharge devices connected in cascade, of a power supply rectifier having an output smoothing filter, the anode of the last discharge device in said cascade connection being connected for unidirectional current through a reactive output device to the input of said filter whereby objectionable amounts of hum currents are supplied to said last discharge device, a resistance connected between the cathode of said last discharge device and said rectifier, and means to supply signal and hum voltage from said resistance to the input of the first discharge device in said cascade connection in degenerative phase, thereby to reduce the hum currents appearing in said out-

put device, said last discharge device having such high impedance that the phase of voltage on said resistance is substantially unaffected by the reactance of said output device over the frequency range over which said amplifier operates, and the total phase shift produced by reactance between the stages of said amplifier being limited to less than ninety degrees at all frequencies within said range, whereby said interstage and output circuit reactances never render said amplifier regenerative.

14. The combination, in a two stage audio amplifier having a reactive output circuit connected between the anode and cathode of the last discharge device in said amplifier, reactance in circuit between said stages, a source of operating potential for the last of said stages producing undesired low frequency variations in said output circuit, and means to reduce said variations, said means comprising a resistance in series with said output circuit, means to supply signal variations and said undesired low frequency variations to the input of the first of said amplifiers in degenerative phase, the anode to cathode impedance of said last discharge device being sufficiently high to prevent the phase of voltage on said resistance from being materially affected by the reactance of said output circuit, whereby the phase shift is substantially limited to that caused by reactance between said stages, the phase shift produced by reactance between said stages being limited to less than ninety degrees at all frequencies at which said amplifier operates, whereby said interstage and output circuit reactances never render said amplifier regenerative.

CHARLES S. ROOT.
